United States Patent

Des. 237,325
Patented Oct. 28, 1975

237,325

SCARF

Mary L. Heath, Arlington, Ind., assignor of a fractional part interest to Raymond Overleese

Filed Jan. 11, 1974, Ser. No. 432,481

Term of patent 14 years

Int. Cl. D2—07

U.S. Cl. D2—358

Fig. 1

Fig. 2

Fig. 3

Fig. 4

FIG. 1 is a front view of a scarf showing my new design;

FIG. 2 is a side view taken in the direction of the arrows 2—2;

FIG. 3 is a back view of the scarf; and

FIG. 4 is a cross sectional view taken on the line 4—4 of FIG. 1.

I claim:

The ornamental design for a scarf, as shown.
